UNITED STATES PATENT OFFICE

160,169

MAN'S SOCK

Salomão J. Haddad, Shrewsbury, Mass., assignor,
by mesne assignments, to Standard Hosiery
Mills, Burlington, N. C., a corporation of North
Carolina

Application June 8, 1950, Serial No. 10,407
Term of patent 14 years

(Cl. D47—7)

To all whom it may concern:

Be it known that I, Salomão J. Haddad, a citizen of the Republic of Brazil, residing at Shrewsbury, in the county of Worcester, Commonwealth of Massachusetts, have invented a new, original, and ornamental Design for a Man's Sock, of which the following is a specification, reference being had to the accompanying drawing, forming a part thereof.

The figure is an elevational view of the sock, showing my new design.

The invention is characterized by a plurality of rectilinear areas of different colors on a sock, the colors of contiguous areas differing from each other with an escalloped junction line between the areas, the scallops extending generally in a course-wise direction. The drawing is lined to indicate contrasting colors.

I claim:

The ornamental design for a man's sock, substantially as shown and described.

SALOMÃO J. HADDAD.
